(57) **CLAIM**

The ornamental design for a laptop desk with adjustable legs, as shown and described.

DESCRIPTION

FIG. 1 is a front elevational view of a laptop desk with adjustable legs showing my new design;

FIG. 2 is a rear elevational view thereof;

FIG. 3 is a left sideview thereof;

FIG. 4 is a right sideview thereof;

FIG. 5 is a top planview thereof;

FIG. 6 is a bottom plan view thereof; and,

FIG. 7 is a perspective view thereof.

The broken lines in the drawing depict portions of the laptop desk with adjustable legs that form no part of the claimed design.
